UNITED STATES PATENT OFFICE.

JOSEF KÖHLEN, OF HERNE, GERMANY.

PERCUSSIVE PNEUMATIC TOOL.

Application filed January 20, 1923, Serial No. 613,888, and in Germany June 6, 1922.

My present invention relates to percussive pneumatic tools such as rock drills, riveting-hammers, pick-hammers and the like. The object of my present invention is to obtain a simple and efficient construction of the operating mechanism of tools of the character referred to above, and particularly to enable an ample supply of air to be governed with the aid of valves of great lightness, and, therefore, having but little momentum.

In the accompanying drawing my invention is shown as applied to a pneumatic rock drill, in which drawing:

Figure 1 is a longitudinal sectional view of the improved rock drill;

Figure 2 is a cross section taken on the line A—B of Figure 1;

Figure 3 is a similar view taken on the same line, but with the multivorous cock in its shut-off position;

Figure 4 is a cross section also taken on the line A—C of Figure 1;

Figure 5 is a longitudinal section taken on the line 5—5 of Figure 2;

Figure 6 is a diagram illustrating the different positions of the multivorous cock, Fig. 7 is a cross section on line 7—7 of Fig. 1 and Fig. 8 is a cross-section on the line A—B of Fig. 1 showing the cock in the position illustrated in Fig. 4.

The pneumatic rock drill provided with my invention comprises a cylinder 1 wherein a piston 2 is reciprocally operated by the motive fluid. To the piston 2 a percussion bar 3 is preferably integrally connected and provided with helical grooves 4 which merge into straight transmitting channels 5 arranged to run parallel with the axis of the rock drill. To impart during the return stroke of the piston a partial rotation to the tool, which may be a tubular drill (not shown), in order to enable the cutting edges of this drill to chip off new particles of stone during the working stroke of the piston, a

chuck 6 is provided, which receives in its squared socket 7 the similarly shaped drill-shank, and besides this is provided with tongues 6' adapted to slide but not to rotate in said transmitting channels 5. Above said tool-holder a sleeve 8 is arranged in a housing 9 which guides said percussion bar and simultaneously serves as intermediate cylinder cover. Said sleeve is provided with tongues 8' in sliding engagement with the walls of the helical grooves 4, although with sufficient play to allow air to pass along the

tongues 8' in the said grooves 4 and adapted to initiate the rotary motion of the percussion bar. The rotation of the tool holder through the instrumentality of the percussion bar is explained by the fact that during the comparatively slow return stroke of the piston the sleeve 8 retains its position in the housing 9 and thus causes the piston and the percussion bar to rotate, whereas during the working stroke of the piston, executed with a far higher velocity, said sleeve is rotated by the percussion bar and thus brought into a position to impart in turn a new partial rotation to the percussion bar during the next return stroke of the piston. The lower part of the sleeve 8 and the tool holder 6 are surrounded by a housing 10 to the lower end of which a drill cage 11 is removably secured.

The motive fluid (generally compressed air) enters the valve chest 12 by way of a supply channel 13 here split up into the two branch channels 14 and 15, of which the former is connected with a valve chamber 16, and the latter with a valve chamber 17. The number of branch channels and valve chambers arranged separately in the valve chest may, of course, be greater than two, if deemed advisable or necessary. In these valve chambers the ball-valves 18 and 19 are arranged severally and each is adapted to alternately open and close diametrically opposed seats formed in the adjacent ends of inlet channels 20 and 21 respectively (Figure 5). Of these channels the channels 20 communicate with the circular cylinder chamber 22 and the channels 21 with the annular cylinder chamber 23 to lead the motive fluid alternately to both piston faces, whereas the spent motive fluid is carried off through the exhaust port or ports 24 and 25 respectively. The ball-valves 18 and 19 work synchronously in parallel and therefore each of them controls but one half of the volume of the motive fluid required for actuating the piston. Since the channels 20 and 21 are of a small cross section the ball-valves 18 and 19 can be small, and therefore light, and besides this they are only required to execute movements of small amplitude, the wear and tear of the valves and their seats is reduced to a minimum.

It is by no means essential that the supply ports be controlled by ball-valves, as shown in the drawing. On the contrary, these ball-valves may be replaced by any type of valve

which in operation is lifted off its seat, or changes its seats, and does not merely slide thereon. The distinctive feature is that there is a plurality of valves instead of the usual single valve.

The admission and the distribution of the motive fluid is controlled in the rock drill illustrated by a multivious cock, here a three-way cock 26, seated in an enlargement 27 of the valve chest 12 and adapted to rotate thereon in an axis parallel with the common axis of cylinder and drill, as shown. The meeting point of the supply channel 13 and of the branch channels 14 and 15 coincides with the axis of the three-way cock and the arrangement of these channels is as illustrated in Figures 1-4 inclusive. In Figure 2 the three-way cock is set for the normal working operation of the rock drill, designated in Figure 6 as position I. When rotated through an angle of 75° the three-way cock attains the position represented in Figure 3, in which position the supply channel 13 is shut-off, which position is indicated in Figure 6 as position II. An additional rotation of the three-way cock through an angle of 45° will bring it into the position illustrated in Figure 4 and is indicated in Figure 6 as position III. In this last position the branch channels 14 and 15 are closed but the supply channel 13 is brought to register with a semi-circular channel 28 connected with a downwardly directed channel 29 of such length that when brought in the position illustrated in Figure 4 it freely communicates with a port 30 which leads to the annular cylinder-chamber 23. In this position of the three-way cock 26 the exhaust port 25 is closed (Figure 4). On the introduction of motive fluid into the annular cylinder-chamber 23 through the channels 13, 28, 29 and the port 30 the piston 2 will be retracted until the helical grooves 4 are brought into communication with the cylinder-chamber 23. During this retraction of the piston a compression of the gaseous contents of the circular cylinder-chamber 22 takes place and prevents the piston 2 from uncovering the exhaust port 24. Since the cross-sectional area of the grooves 4 is not completely closed by the tongues 8', nor that of the transmitting channels 5 by the tongues 6', the live motive fluid admitted to the annular cylinder chamber 23 can pass freely through these channels, advance through the tubular drill to the bottom of the bore-hole, and completely remove the stone-dust from the latter by blowing it upward and out of the mouth of the bore-hole. When the live motive fluid on its downward way reaches the recess 31 of the tubular tool holder a part of it flows through a central longitudinal bore 32, common to percussion bar and piston, into the circular cylinder-chamber 22 and equalizes the pressure on the upper piston face and the pressure on the end of the percussion bar and on the annular lower pis-

ton face. As the equilibrium of the piston is thus assured the piston is held by friction in the position assumed to keep the exhaust port 24 closed. When shallow bore-holes are driven into dry rock the small jet of motive fluid which passes at each working stroke of the piston through the longitudinal bore 32 to the bottom of the bore-hole suffices to blow out the stone-dust but in all other cases it is preferably blown out as indicated above.

Since the general operation of the rock drill is well known in all its phases, and besides this may be readily understood with the aid of the accompanying drawing, a detailed description of it is deemed superfluous.

The several parts of the drill are kept in alignment and resilient contact one with another by bolts 33 which pass through the external cylinder cover 34 provided with a handle 35 and through lateral lugs 36 of the housing 10 between which lugs and the nuts 37 of the bolts helical springs 38 are arranged, as indicated by dotted lines in Figure 1.

In conclusion it may be pointed out that the utility of the multivious cock is by no means confined to the multiple inlet valve mechanism shown, although it operates particularly advantageous in combination therewith. The utility of this cock, though intended for a simultaneous distribution of motive fluid to a plurality of inlet valves, is by no means restricted to such multiple inlet valve mechanism, for it can also be used very advantageously where only a single inlet valve is employed.

I claim:

1. A percussive pneumatic tool comprising a cylinder and a piston arranged to reciprocate therein, said cylinder having two exhaust ports arranged to be uncovered by the piston alternately but so located that in certain positions of the piston both exhaust ports will be covered thereby, a cock which controls the one exhaust port of the cylinder, and channels, likewise controlled by said cock, for leading the medium under pressure alternately to opposite ends of said cylinder, said cock being arranged to conduct the medium under pressure to one end of the cylinder at the same time that said cock closes the exhaust port leading from that cylinder end.

2. A percussive pneumatic tool comprising a cylinder and a piston arranged to reciprocate therein, and provided with a percussion bar held to reciprocate with said piston and provided with grooves arranged to communicate at times with one end of said cylinder to allow the motive medium under pressure to blow out at the surface worked by the tool, said cylinder having two exhaust ports arranged to be uncovered by said piston alternately, and a cock for admitting motive fluid under pressure or shutting off such fluid, to or from channels leading to opposite ends of the cylinder, said cock also having a position

in which it shuts off the exhaust port of that cylinder end which is adapted to communicate with the grooves of the percussion bar, while at the same time admitting fluid under pressure to said end.

3. A percussive pneumatic tool comprising a cylinder, a piston arranged to reciprocate therein, and a percussion bar held to reciprocate with said piston and provided with channels arranged to communicate at times with one end of the cylinder to allow the motive fluid under pressure to blow out at the surface worked by the tool, said cylinder being provided with channels to admit such fluid under pressure alternately to opposite ends of the cylinder, and also having exhaust ports arranged to be uncovered by said piston alternately, and a cock which in one position opens the exhaust port for that end of the cylinder through which the percussion bar extends, and at the same time admits the motive fluid to said cylinder channels alternately, while in another position said cock shuts off the admission of motive fluid entirely while still leaving the exhaust port open, and in a third position said cock closes said exhaust port, but admits motive fluid to the cylinder end adjacent to said exhaust port.

4. A percussive pneumatic tool comprising a cylinder having inlet ports at opposite ends and exhaust ports at different distances from its ends, a piston arranged to reciprocate in said cylinder and controlling the exhaust ports thereof, a percussion bar held to reciprocate with said piston and provided with grooves arranged to communicate at times with one end of said cylinder to allow the motive medium under pressure to blow out at the surface worked by the tool, the said piston and percussion bar being provided with a longitudinal channel communicating with the other end of the cylinder, and a cock controlling the outlet of the exhaust port which is connected with the cylinder end containing the percussion bar, said cock also operating to establish or shut off the supply of motive fluid to the ends of the cylinder.

5. A percussive pneumatic tool comprising a cylinder provided with a plurality of valve chambers, means for admitting like

amounts of a pressure medium to each of said valve chambers, a piston arranged to reciprocate in said cylinder, channels for conducting said medium under pressure from each of said valve chambers to opposite ends of said cylinder; and floating valves of like weight, constructions and stroke solely operated by said pressure medium and arranged to move coincidentally and in parallel in the respective valve chambers and operating to connect these chambers with opposite ends of the cylinder alternately.

6. A percussive pneumatic tool comprising a cylinder provided with a pair of valve chambers arranged side by side, branch channels connecting said valve chambers independently of each other with the inlet of a pressure medium and adapted to admit like amounts of such pressure medium to each of said valve chambers, a piston arranged to reciprocate in said cylinder, channels for conducting said medium under pressure from each of said valve chambers to opposite ends of said cylinder, and two floating ball valves of like weight and stroke solely operated by said pressure medium and arranged to move coincidentally and in parallel in the respective valve chambers and operating to connect these chambers with opposite ends of the cylinder alternately.

7. A percussive pneumatic tool comprising a cylinder provided with a plurality of valve chambers, a piston arranged to reciprocate in said cylinder, channels for conducting a medium under pressure from each of said chambers to opposite ends of said cylinder; and a single distributing cock adjustable to one position for admitting like amounts of such pressure medium simultaneously to each of said valve chambers, and to another position for shutting off the supply of such medium from said chambers and to lead said medium through the front end of the cylinder to the bore hole of the tool when said piston on its return stroke reaches a certain position in the cylinder.

Signed by me at Cologne, Germany, this 28th day of December, 1922.

JOSEF KÖHLEN.
